BROOM HOLDER

Herman Sokoloff, Kansas City, Mo.

Application January 22, 1944, Serial No. 519,265

3 Claims. (Cl. 15—177)

1

This invention relates to the broom and mop making art and particularly, to devices for detachably connecting the fibers of a broom to a handle.

In the manufacture of brooms it has long been common practice to permanently anchor the handle to the broom fibers. After the fibers have become worn to the extent that the broom is no longer useful, the handle must also be discarded.

It is the principal object of this invention therefore, to provide a device for detachably securing a handle to a broom in a simple and effective manner, thereby permitting the use of a single handle for a series of brooms.

This invention has for a further aim to provide a connector or holder of the above character, having embodied therein unique clamping means for firmly anchoring the connector to the broom fibers without the use of tools or the like.

A yet further aim of this invention is the provision of a connector having mating halves joined together in a manner to permit spreading of the jaw portions thereof, to facilitate mounting of the holder on the broom fibers.

Other objects of the invention will appear during the course of the following specification, referring to the accompanying drawing, wherein:

Fig. 1 is a perspective view of a broom joined to a handle by a holder or connector constructed in accordance with the preferred form of this invention.

Fig. 2 is a perspective view of the preferred form of holder in removed condition from a broom, shown fragmentarily.

Fig. 3 is a cross section of the holder taken on line III—III of Fig. 2.

Fig. 4 is a cross section of the connector taken on line IV—IV of Fig. 1; and

Fig. 5 is a perspective view of a modified form of holder, a handle portion positioned therein being indicated in dotted lines.

In the preferred form of invention illustrated in Figs. 1 to 4 of the drawing, the numeral 10 designates a hood-shaped holder or connector for joining the broom fibers 12 to a handle 14.

Holder 10 comprises a pair of mating members 16 formed of sheet metal, plastic or any other suitable substance, and having inwardly curved, upper arcuate edges 18, spaced slightly from each other. At the upper center of members 16 are semi-circular extensions or projections 20 likewise spaced from each other and serving to form a ferrule for handle 14.

Reinforcing beads 22 of arcuate cross section

2

bridge the spaced upper edges 18 of members 16 and extend along these edges from a point near the lower edges 24 of members 16 to the upper ends of extensions 20. It should be noted that the opposite edges of beads 22 are soldered, welded or otherwise fixed throughout their length of the respective opposite halves of holder 10, excepting for that portion of each bead which extends along projection 20. As is clearly shown in Figs. 2 and 4, only one edge of one bead is fastened to the projecting portion 20 of one member 16, while one edge of the other bead is secured to the extension of the remaining member 16. Likewise, it will be clear from these figures that each bead is slit, as indicated at 26, from its lower edge to a point adjacent its zone of juncture with extensions 20. By reason of this unique structure, it is possible to spread the lower or jaw edges 24 of members 16 apart to facilitate mounting of the holder over the upper ends 28 of the broom fibers 12. It is further possible to firmly clamp the extensions 20 against the broom handle 14. The latter may be accomplished by passing a bolt 30 through an aperture 32 in one extension, through a hole 34 in handle 14, and threading it into an opening 36 in the opposite extension. A head 38 on the bolt 30 in the form of a thumb nut, simplifies the procedure of attaching and removing the holder from the handle.

30 A band 40, secured at its approximate center to one of the mating members 16, near its lower edge, terminates at one end in spaced ears 42 between which is pivotally mounted a locking arm 44. The other end of the band is provided with an opening 46 for receiving the locking arm which is projected therethrough and employed as a lever for drawing the band tightly around the holder. Opening 46 is sufficiently large to receive ears 42, which rest therein when the band has been fully contracted and, in this condition, a loop 48 slidably mounted on the band is moved over arm 44, as shown in Fig. 1, to maintain the jaw portions of members 16 in tight engagement with the upper end of broom 12. Spurs or protuberances 50 extending inwardly from members 16 adjacent their lower edges, further assist in preventing dislodgment of the broom from the holder when band 40 is contracted.

35 The manner of attaching a handle 14 to a broom 12 with a holder 10 constructed as described, will be clear from the foregoing.

40 It will be found preferable to first mount the holder on the broom since obviously, the jaw edges of the former may be more readily spread if the extensions 20 are free to move toward each other.

Beads 22, therefore, serve not only as flexible connections for joining the mating members 16, but also as reinforcing strips to strengthen the upper edges of these members, together with the ferrule portion of holder 10.

In the modified form of invention illustrated in Fig. 5, the construction of the holder 60 is similar to that of holder 10, but in the latter form the mating members 62 are completely separated from each other. A band 64, much like 10 band 22, is provided with a modified type of fastener comprising an arm or lever 66, pivoted to one end of the band and a link 68 pivotally joining the opposite end of the band to the arm intermediate its ends. When arm 66 is swung on its pivot to tighten band 64, it is held in place by a loop 70 slidably mounted on the band. Co-operating extensions 72 on each of members 62 may be fastened to handle 14 in exactly the same manner as that employed in the preferred form. If desired, however, one of the extensions 72 may be rigidly secured to the handle before the broom 12 is mounted in one-half of the holder, whereupon the other half of the holder is positioned in place and fastened to the handle.

Throughout the specification, this invention has been referred to as being particularly applicable for connecting a broom to a handle, but obviously, it would be equally practical for removably connecting certain types of mops and other articles to handle members.

From the foregoing it will be apparent that the objects of this invention have been accomplished and, while it is conceivable that other modifications might be made without departing from the spirit of the invention, it is desired to be limited only by the scope of the appended claims.

Having thus described the invention, what is claimed as new and desired to be secured by Letters Patent is:

1. In a device of the character described, a holder comprising a pair of mating members, each having an extension in its upper end for

receiving a handle therebetween; reinforcing beads having their opposed marginal edges overlapping said pair of members and secured thereto to hold the members in spaced apart relation to each other, said beads being slit longitudinally throughout a portion of their length to permit limited spreading of the members when mounting said holder on a broom; and means for drawing said spaced members toward each other.

2. In a device of the character described, a holder comprising a pair of mating members each having an extension on its upper end, said extensions combining to form a ferrule for a handle, said members having parallel lower jaw portions; reinforcing beads having their opposed marginal edges secured to said pair of members from their lower jaw portions to the extensions, said beads being longitudinally slit throughout a portion of their length at the edges of the jaw portions opposite the ferrule to permit flaring of the members when mounting said holder on a broom; and means for drawing the jaw portions of said spaced members toward each other.

3. In a device of the character described, a holder comprising a pair of mating members each having an extension on its upper end, said extensions combining to form a ferrule for a handle, said members having parallel lower jaw edges; beads having opposed edges secured to said pair of members from their lower jaw edges to the extensions, one bead having one edge secured to the extension of one member, the other bead having one edge secured to the extension of the other member, said beads being slit from their lower edges to a point adjacent the extensions to permit limited spreading of the jaw edges when mounting said holder on a broom, and to simultaneously permit movement of said extensions toward each other; and means for clamping the jaw edges of the members against opposite sides of a broom.

HERMAN SOKOLOFF.
